A. T. T. 1902.

UNITED STATES PATENT OFFICE.

THEODORE HAUSER, OF CHICAGO, ILLINOIS, ASSIGNOR TO THE GARVY COMPANY, OF CHICAGO, ILLINOIS, A CORPORATION OF ILLINOIS.

CONVERTIBLE LOUNGE.

SPECIFICATION forming part of Letters Patent No. 716,634, dated December 23, 1902.

Application filed December 4, 1901. Serial No. 84,639. (No model.)

To all whom it may concern:

Be it known that I, THEODORE HAUSER, a citizen of the United States, residing at Chicago, in the county of Cook and State of Illinois, have invented new and useful Improvements in Convertible Lounges, of which the following is a specification.

My invention relates particularly to an improved lock for a swinging leaf of a convertible lounge or sofa-bed; and my primary object is to provide a lock of simple and inexpensive construction capable of locking automatically to secure the swinging leaf in a horizontal position and releasing automatically to permit said swinging leaf to be lowered.

My invention is illustrated in its preferred form in the accompanying drawings, in which—

Figure 1 is an end view of a convertible lounge, couch, or sofa-bed equipped with my improvements; Fig. 2, a broken sectional view taken parallel to an end of the couch and looking at the end from the inner side thereof, said view showing the folding leaf, to which my present invention relates, in a depressed position; Fig. 3, a similar view showing said folding leaf elevated to the horizontal position and locked in said position; Fig. 4, a broken horizontal section taken as indicated at line 4 of Fig. 3; and Fig. 5, a view similar to Fig. 3, but showing the swinging leaf elevated somewhat above the horizontal position to bring the automatic release into operation.

In a couch of the general construction here shown the main parts are a stationary horizontal seat-frame A, a rear swinging leaf B, capable of assuming either of three positions, and a front swinging leaf C, capable of assuming either of two positions. The drawings show the leaf B provided with a lock D, which is described in detail and claimed in my application of even date, Serial No. 84,638. The swinging leaf C is provided with a locking device E capable of automatic engagement and release, said locking device forming the subject-matter of the present application.

The seat-frame A is supported on end standards F, (one only shown,) said end standards being connected by longitudinally-extending members G. (One only shown.) The end

standards preferably include upright angle-irons a a' .

Each locking device E, of which there preferably is one located at each end of the lounge, comprises a locking member b, pivotally connected at one end by means of a pivot b' with the leaf C and provided at the other end with a notch b², affording shoulders b³ b⁴, and provided adjacent to said notch with an offset end b⁵ and a releasing member c, depending from a pivot c' with which the seat-frame A is provided outside the upright a', said releasing member having at its lower end a loop c² for receiving loosely the member b. The member b passes loosely through a slot d with which the upright a is provided, the lower end of said slot affording a shoulder d', with which the shoulder b³ of the notch b² lockingly engages to hold the leaf C in a horizontal position, as illustrated in Fig. 3. The member c preferably is formed with a curve or offset at c², the purpose of which is to cause the lower end of said member to swing close to the lower wall of the slot d under certain conditions, this being accomplished, as is evident, by the proper location of the center of gravity of the member. When the leaf C is raised to the horizontal position of Fig. 3, the shoulder b³ drops over the lower wall of the slot, the weight of the member b being sufficient to push the lower end of the member c away from the upright a', as shown in Fig. 3. When the leaf C is raised to the position shown in Fig. 5, the lower end of the member b is swung upwardly somewhat by reason of the shoulder b⁴ coming in contact with the upright a', thus permitting the loop of the member c to pass beneath the shoulder b³. If now the leaf C be quickly raised and allowed to fall, the member c will serve to carry the shoulder b³ over the lower wall of the slot d, thereby effecting a release from the locking engagement. In practice the leaf C is given a quick slight upward movement from the position shown in Fig. 3 and is then quickly lowered, thereby causing the release to take place without any difficulty.

Couches of the description herein shown are generally composed entirely of metal, the frame being preferably principally of steel

angle-irons, the seat-frame and swinging leaves being provided with a suitable wire-netting. Removable mattresses are usually employed in connection with the couches.

5 It will be understood that this article of furniture may be employed in either of three positions: first, the leaves B and C may both be dropped to a depending vertical position; second, said leaves may both be brought to a horizontal position, thereby affording a bed, and, third, the leaf C may be brought to a vertical depending position and the leaf B to the standing position indicated in full lines in Fig. 1, thereby affording a sofa-bed having a back. It will be understood that the offset ends b^5 prevent the links b from being wholly withdrawn from the slots d .

Changes in details of construction within the spirit of my invention may be made. 20 Hence no undue limitation is to be understood from the foregoing detailed description.

What I claim as new, and desire to secure by Letters Patent, is—

1. In an article of the character described, 25 the combination of a seat-frame, a suitable support therefor, a swinging depending leaf, a locking-link connected with said leaf and provided with a locking-shoulder, a stationary locking-shoulder engaged by said first-named shoulder, and an automatic pivoted depending releasing-link moved through the medium of said first-named link and with which said first-named link slidably engages.

2. In an article of the character described, 35 the combination with a stationary seat-frame, and a depending swinging leaf, of locking and releasing means, comprising a leaf-carried pivoted locking-link provided with a locking-shoulder, a stationary locking-shoulder upon 40 which said link slides, and an automatic depending releasing-link moved through the medium of said first-named link having a guide for said locking-link, said guide serving during release to hold said link-carried 45 locking-shoulder out of engagement with said stationary shoulder.

3. In an article of the character described, 50 the combination with a stationary seat-frame, and a depending swinging leaf, of locking and releasing means, comprising a stationary guide, a notched leaf-carried locking-link provided with means for preventing complete withdrawal from said guide, and a gravity-

acting releasing-link pivotally supported from said seat-frame and having a link-receiving guide adjacent to said stationary guide. 55

4. In an article of the character described, the combination with a stationary frame provided with a stationary guide and locking-shoulder, and a depending swinging leaf, of a leaf-carried locking-link provided toward its free end with a locking-shoulder, and a movable releasing-link on said frame frictionally engaged by said locking-link and 60 moved outwardly thereby during the elevation of the leaf to the horizontal position to permit said locking-link to lock, said releasing-link being relieved from said frictional engagement by further elevation of said leaf 65 and permitted to move inwardly into position to carry the locking-shoulder of the locking-link over the stationary locking-shoulder when the leaf is dropped. 70

5. In an article of the character described, 75 the combination with a stationary frame having a stationary guide and locking-shoulder, and a swinging depending leaf, of a locking-link connected with said leaf and provided with a shoulder for engaging said first-named 80 shoulder, and a pivoted depending releasing-link on the outside of said frame having a projection frictionally engaged by the locking-link and having a bend tending to throw the lower extremity of the link close to the 85 stationary locking-shoulder, for the purpose set forth.

6. In an article of the character described, the combination with a stationary frame provided with a stationary guide and locking-shoulder, and a pivoted depending leaf, of a leaf-carried locking-link extending through 90 said guide and provided with a locking-shoulder, and a releasing-link pivotally supported on said frame and engaging said locking-link 95 and moved automatically into the releasing position during the elevation of the leaf above the horizontal position and serving to carry the link-carried locking-shoulder over the stationary locking-shoulder when the leaf is 100 dropped, for the purpose set forth.

THEODORE HAUSER.

In presence of—

ALBERT D. BACCI,
WM. B. DAVIES.
